UNITED STATES PATENT OFFICE.

BRIGET APICHELLA, OF MARION HEIGHTS BOROUGH, PENNSYLVANIA.

CUFF FOR MEN'S SHIRTS.

1,209,798.

Specification of Letters Patent. Patented Dec. 26, 1916.

Application filed May 31, 1916. Serial No. 100,750.

To all whom it may concern:

Be it known that I, BRIGET APICHELLA, a subject of the King of Italy, residing at Marion Heights Borough, in the county of 5 Northumberland and State of Pennsylvania, have invented certain new and useful Improvements in Cuffs for Men's Shirts, of which the following is a specification, reference being had therein to the accompanying 10 drawing.

This invention relates to improvements in men's shirts, and particularly to improvements in sleeve cuffs of the kind commonly known as "soft cuffs" of the turn-back 15 variety.

In cuffs of this character as ordinarily constructed the meeting edges of the inner fold of the cuff proper are arranged, when closed, to lie with their inner faces inlapping engagement, and such edges are provided with button-holes for the passage of the cuff button, which also passes through button-holes in the outer folds of the cuff. The objection to this construction is that 20 the cuff, even when held fully closed by the button, is liable to undesirably gap, and the cuff in many respects does not present a neat and finished appearance.

One object of the present invention is to 25 provide a construction of cuff wherein these objections are avoided by providing the meeting edges of the outer folds of the cuff only with openings for the passage of the cuff button and constructing the meeting 30 edges of the inner fold of the cuff to be fastened independently of the cuff button, whereby the cuff will be kept closed and gapping at the meeting edges will be avoided.

A further object of the invention is to 35 provide a cuff construction of the character described wherein the meeting edges of the inner fold are also adapted to overlap with the inner face of the outer edge overlying the outer face of the inner edge, combined 40 with means for fastening the edges together in such relationship, whereby a positive closure of the cuff and prevention of a gap 45 is secured.

The invention consists in the features of 50 construction and combination and arrangement of parts hereinafter more fully described and claimed, reference being had to the accompanying drawings, in which—

Figure 1 is an edge view looking toward 55 the outer side of a portion of the sleeve and cuff of a shirt embodying my invention,

showing the parts fastened in closed position; Fig. 2 is a section on the line 2—2 of Fig. 1; Fig. 3 is a view similar to Fig. 1, showing the meeting ends of the outer fold 60 of the cuff turned back to expose the meeting ends of the inner fold thereof; and Fig. 4 is a side view looking toward the meeting edges of the cuff and showing the outer fold turned out into the plane of the inner fold 65 of the cuff.

Referring now more particularly to the drawings, I designate the sleeve of a shirt, provided with the usual placket having the meeting edges 2 and 3 and terminating in 70 the cuff 4 composed of the inner fold 5 and outer fold 6, the latter being turned backward, as usual, over the outer surface of the inner fold. It will, of course, be understood that the cuff may be made in general of ordinary construction and of any desired number of plies of material, the difference between the improved cuff and cuffs of ordinary construction being in the features hereinafter described. 80

As shown, the meeting edge 2 of the sleeve placket may be provided with a button-hole 7 to receive a button 8 upon the meeting edge 3 of said placket, for the purpose of closing the placket at a point in proximity to the 85 cuff, and, as shown, the inner fold 5 of the cuff is provided, in accordance with my invention, with extensions 9 and 10 which project beyond the normal line of the corresponding edges of the outer fold 6 of the 90 cuff, which edges of said outer fold are provided as usual with button-holes 11 for the passage of the usual cuff button 12, which may be of the link type commonly employed. 95

The edges 9 and 10 of the inner fold 5 are adapted to overlap to close the placket portion of the cuff when the cuff is closed as in use, the edge extension 9 being arranged to overlap the end extension 10, with the surface of said edge extension 9 lying against 100 the outer surface of the end extension 10, so that said edge extensions overlie each other in the general extension of the material of the cuff to complete the formation of a closed band, whereby the cuff will be completely 105 closed and the formation of a gap or opening prevented. For the purpose of holding the edges 9 and 10 in such position, the edge 9 may be provided with a button-hole 13 to engage a button 14 on the edge 10, or any 110 other suitable type of fastening means for the purpose may be employed.

It will thus be understood that in use the inner fold of the cuff may be arranged to completely encircle the wrist of the wearer and be closed and held in closed position, while the meeting edges of the outer fold of the cuff will be united exclusively of the meeting edges of the inner fold by the ordinary cuff button, the arrangement being such that the edges of the outer fold are visibly united in the usual way while the edges of the inner fold are united in overlapping relationship, thus making a neater connection and preventing any unsightly gaps.

15 Other objects and advantages of the invention will be apparent from the foregoing description.

I claim as my invention:

1. A cuff of the turn-down variety for shirts comprising a cuff body including an inner fold and an outer fold, the inner fold having edge extensions which are adapted to overlap with the inner face of the outer extension lying in contact with the outer face of the inner extension when said extensions are brought into overlapping engagement, said extensions being provided with means for securing the same in overlapping relation, and the meeting edges of the outer

fold being arranged to extend laterally beyond the line of the overlapping edges of the inner fold and provided with button holes, whereby said meeting edges of the outer fold may be connected independently of the meeting edges of the inner fold by an ordinary form of cuff button laterally beyond the overlapped and secured meeting edges of the inner fold.

2. A soft cuff of the turn-down variety for shirts comprising a cuff body including an inner fold and an outer fold, the inner fold having edge extensions which are adapted to overlap with the inner face of the outer extension lying in contact with the outer face of the inner extension when said extensions are brought into overlapping engagement, one of said extensions being provided with a button-hole and the other with a button to engage said button-hole, and the meeting edges of the outer fold being provided with button-holes to receive an ordinary form of cuff button.

In testimony whereof I hereunto affix my signature in the presence of two witnesses.

BRIGET APICHELLA.
